JIG FOR MAKING PICTURE FRAMES

James R. Huntley, 309 W. Crowell St.,
Monroe, N.C. 28110

Filed May 13, 1974, Ser. No. 469,471

Term of patent 14 years

Int. Cl. D8—05

U.S. Cl. D8—72

FIG. 1 is a perspective view of a jig for making picture frames showing my new design;

FIG. 2 is a top plan view thereof on a reduced scale;

FIG. 3 is a side elevational view thereof on a reduced scale looking in the direction of arrow 3 of FIG. 1; and

FIG. 4 is another side elevational view thereof on a reduced scale looking in the direction of arrow 4 of FIG. 1.

I claim:

The ornamental design for a jig for making picture frames, substantially as shown.
